MILLING MACHINE

Robert S. Condon, Rutland, Vt.

Application June 8, 1942, Serial No. 446,211

17 Claims. (Cl. 90—21)

This invention relates to milling machines, and the principal object is to provide a knee and column type horizontal milling machine which is fitted with a heavy swingable vertical head which virtually transforms the machine into a vertical milling machine when the vertical head is swung about its hinge into operating position and bolted or otherwise locked in such position.

Another object of the invention is to provide the machine with a novel knee brace which ties the front or outer portion of the knee to the base casting.

A further object of this invention is to provide the machine with means for obtaining direct reading of the infinitely variable speeds.

A further object of this invention is to provide the machine with a dog controlled automatic longitudinal table cycle accomplished by both mechanical and electrical means.

A still further object of this invention is to provide the machine with a novel interlock which prevents the engagement of the table hand crank when the table screw is rapidly rotating under power feed or power rapid traverse.

Other minor objects will be hereinafter set forth.

I will explain the invention with reference to the accompanying drawings which illustrate several practical embodiments thereof, to enable others familiar with the art to adopt and use the same; and will summarize in the claims the essential feature of the invention, the novel features of construction, and novel combinations of parts, for which protection is desired.

In said drawings:

Fig. 1 is a transverse vertical section through the horizontal milling machine showing knee brace.

Fig. 2 is a front elevation of the vertical milling head showing the hinged mounting.

Fig. 3 is a vertical section through the vertical milling head.

Fig. 4 is a horizontal section through the column of the machine showing the double V-belt selector.

Fig. 5 is a front elevation of the dial and pointer which directly indicate the speed of the spindle.

Fig. 6 is a horizontal section through the speed back gear selector.

Fig. 7 is a developed horizontal section showing the mechanical feed table drive.

Fig. 8 is a plan view of the table hand crank safety interlock.

Fig. 9 is a diagram of the electrical circuit.

Fig. 10 is a vertical section of the dial feed rate selector.

Fig. 11 is a transverse section through the dial feed rate selector mechanism.

Fig. 12 is a plan view of the alternate speed back selector.

Fig. 13 is a partial transverse vertical section through the horizontal milling machine showing the alternate heavy duty back gears.

Fig. 14 is an enlarged section on the line 14—14, Fig. 7.

Fig. 15 is a perspective view of the safety interlock.

In the drawings, the numeral 10 designates the column of the milling machine, while 11 designates the base, 12 the knee, 13 the saddle, and 14 the table.

The horizontal spindle drive

20 The drive to horizontal spindle 25 in column 10 is powered by an electric motor 26 (Fig. 1) which is equipped with a stopping brake 27. A V-belt pulley 28 is keyed to motor shaft 26a and drives a V-belt 29 which drives intermediate shaft 30 through spring loaded pulleys 31b and 31c (Figs. 1 and 4). Intermediate shaft bracket 32 is supported on pivot 33 by projecting lugs 32a and 32b. The spindle drive continues through V-belt 34 which engages V-pulleys 31a and 31b on intermediate shaft 30 and also engages V-pulley 35 on drive sleeve 36 (Fig. 1). Drive sleeve 36 is journaled in bearings in bracket 37 and carries a small drive pinion 36a. Drive bracket 37 is bolted to bracket 38 and is also attached to and supported on column 10.

Drive pinion 36a is in constant mesh with gear 39a of cluster gear 39a, 39b, which cluster is keyed to countershaft 39. The drive is completed to spindle 25 through gear 39b which meshes with gear 25b since cluster gear 25b, 25c is splined to spindle 25. Cluster gear 25b, 25c can be shifted on spindle 25 to the right (Fig. 1) to bring pinion 39c into mesh with gear 25c, pinion 39c being also keyed to shaft 39. Also cluster gear 25b, 25c can be shifted to the left (Fig. 1) until the clutch teeth 36x on pinion 36a engage internal clutch teeth within the hub of gear 25b. Thus the drive from sleeve 36 can be direct to spindle 25; or may be through pinion 36a to gear 39a, and thence either through 39b to gear 25b, or through pinion 39c to gear 25c, providing three different speeds for spindle 25.

The belt speed change mechanism

55 The V-belts 29 and 34 are maintained in ten-

sion by spring 31d which is backed by nut 31e and forces the keyed but slidably V-pulley cone 31a on shaft 30 inwardly against V-belt 34. This force against belt 34 is transmitted to double cone V-pulley 31b which is keyed but slidably mounted on shaft 30, and which presses against V-belt 29, the V-belt 29 in turn pressing against V-pulley cone 31c which is pinned to shaft 30. When the V-pulley cones 31a, 31b and 31c are lowered by depressing shaft 30, the V-belt 29 assumes a position on its pulley cones 31b, 31c at a greater radius, and V-belt 34 assumes a position on its V-pulley cones 31a, 31b at a shorter radius by the free shift of double cone 31b, and thus the speed of the pulley 35 and of spindle 25 is reduced. The raising of shaft 30 which is journaled in bracket 32 will correspondingly increase the speed of pulley 35 and of spindle 25.

The means for raising and lowering the double V-belt cones 31a, 31b and 31c consists of a screw 40 (Figs. 1 and 4) journaled in the column 10 at 40a and 40b (Fig. 4) and rotated by hand wheel 40c. This threaded screw 40 operates in a nut 41 which is pivoted in a yoke 42 on cross pivots 42x. The projection 42a from yoke 42 (Fig. 1) is journaled in projections on bracket 32 at 32c and 32d in rotatable and slidably bearings. As hand wheel 40c is rotated, nut 41 is adjusted along the screw 40, and nut 41 pivots in yoke 42 and carries the yoke with it. As the yoke 42 is moved by nut 41 the projection 42a of the yoke rotates bracket 32 in projecting lugs 32a and 32b, and at the same time moves bracket 32 along the pivot shaft 33. Thus as double V-belt cone pulleys 31a, 31b and 31c are raised and lowered to accomplish a belt speed change, same are moved laterally to maintain the alignment of V-belts 29 and 34.

The belt speed indicator

The indication of the belt speed is shown by pointer 43 on dial plate 44 (Fig. 5). Pointer 43 is rotated by pin 41a engaging a spiral groove 45a in a pointer shaft 45. As the nut 41 is moved by the hand wheel 40c the pin 41a in said nut rotates the pointer shaft 45 and thus turns the pointer a corresponding amount. Dial plate 44 is mounted so that it can be adjustably positioned about pointer shaft 45. This is accomplished by any convenient means such as that shown in Fig. 5 using two screws 42a passing through arcuate slots 42b in dial 44 and entering column 10. The dial can thus be properly positioned after the final assembly of the machine by obtaining actual readings of one spindle speed and setting the dial plate 44 so that the pointer 43 will indicate thereon the correct speed reading. The adjustment feature of the dial plate 44 is further advantageous in event the belt 34 wears or stretches and therefore assumes a new position on its cone pulleys 31a and 31b. In this event the cone pulley shaft 30 can be lowered by rotating the hand wheel 40c. The amount that pointer 43 is moved in order to bring belt 34 back to proper operating position can be compensated by adjusting dial plate 44 to bring the pointer indication of speed to the correct reading. In event of undue wear or stretch in belts 29 or 34, the motor 26 can be lowered by sliding the motor supporting bolts in slots 10x in column 10 so that belts 34 and 29 can be again brought into their correct operating positions on pulley cones 31a, 31b and 31c.

The above arrangement provides a drive which will transmit high power since the belts 29 and 34 are maintained at high peripheral speed. High

torque is obtained through gear train 36a, 39a, direct to the spindle 25 through gears 39b and 25b, or through gears 39c and 25c; and thus high torque, for slow spindle speeds, is not created until the drive has progressed to a point immediately adjacent the spindle 25. The gears in the above drive are so chosen that the range of speeds developed by the belts 29 and 34 through each gear train will produce a continuous infinite speed range from minimum to maximum. The three divisions of this complete range is shown on dial 44 in Fig. 5.

The means for shifting cluster gears 25b, 25c

The shifting of cluster gear 25b, 25c, is accomplished by means of a yoke bracket 50 (Fig. 6) the yoke extension 50x which projects between gears 25b and 25c. Yoke bracket 50 is shifted by rod 51 which is moved laterally by spur gear 52a meshing with rack teeth 61y on said rod 51. Shaft 52 to which spur gear 52a is keyed, also carries a hand knob 52b. Locking pin 52c locks hand knob 52b in position against supporting bracket 53. Spring 53a functions to force 52b in position against supporting bracket 53. Spring 53a functions to hold locking pin 52c into engagement with holes in bracket 53 since the pressure of spring 53a is backed by supporting bracket 53 and acts against sleeve 52d which engages the spur gear 52a.

A spring 50a (Fig. 6) is compressed between two C-shaped collars 51x at each end of a reduced portion of shifting rod 51, as shown. The two collars 51x at each end of this reduced portion are also held in shifter bracket 50 by collar 51z. Thus rod 51 may be moved in either direction without carrying shifter bracket 50 with it, but in so doing bracket 50 is put under spring pressure to move in said direction. Therefore hand knob 52b can be moved to position the cluster gears 25b and 25c either for clutch engagement with pinion 36x, or gear engagement with cluster gears 39b or 39c by first pulling out hand knob 52b and turning same to the correct position and allowing spring 53a to bring pin 52a into its desired hole or position. If the gears of the cluster 25b, 25c should strike the faces of the cluster gear 39b, 39c, or against the face of the clutch teeth 36x so that shifter bracket 50 would be unable to directly move, then shifter rod 51 would compress spring 50a and yieldably place shifter bracket 50 under tension, so that when the motor 26 was actuated the shifter 50 would carry the sliding cluster gear 25b, 25c, into correct mesh as soon as the gear teeth or clutch teeth were rotated into the correct position to mesh.

The knee brace

In Fig. 1, the numeral 60 designates the knee brace. The base 11 of the milling machine houses the motor 26 together with its brake 27, as previously stated, also a sump 11a, and the lower end of a one-piece elevating screw 13d. The shape of the base is so designed that a projection from the catch pan 11b forms a rigid support for a clamp 60a for clamping the knee brace 60 which is secured to the forward end of knee 12 as at 60b. Knee 12 engages ways 10a (Fig. 4) on column 10. Knee brace 60 therefore serves as an additional support for the knee 12, and since the knee 12 is already well supported with an extended gibbed slide 12a, the knee on my milling machine is exceptionally well supported. Either one clamp 60a is used, or more than one may be used in which latter case the

clamps 60a are separated and placed adjacent each side of the base, and mounting 60b being extended to embrace each side of knee 12. Thus the knee brace 60 not only supports the knee 12 vertically but also resists any transverse deflection of knee about its ways 10a (see Fig. 1).

The arbor and its support

The overarms 65 are journaled in bores in both outer walls of column 10 as well as in the center wall as shown. Clamping of the overarms 65 is accomplished by one clamping lever 66a which draws equalizing shoe 66 up between and against overarms 65. When lever 66 is rotated its screw draws shoe 66 up by means of the screw threads shown, the pressure being equalized between the two ends of said shoe. The overarms 65 are thus bound upwardly and outwardly against their respective bores in column 10.

Arbor support 61 is split horizontally at 61b and is clamped to overarms 65 by utilizing clamp 61a which draws the upper half of arbor support 61 down against the lower half by the action of screw which engages screw threads in the lower half as shown. The cutters 68 are held on arbor 69 by the usual series of spacing sleeves and a nut as shown. The one bushing of the arbor 69 is journaled in the support 61, and arbor 69 is held in spindle 25 by forcing the tapered end of the arbor into the tapered spindle nose.

The cooling system

The coolant in my milling machine is raised through piping 11x from sump 11a by a pump 50 which is driven through coupling 50a by motor 50b as shown. The coolant is then piped from pump 50 to a flexible conduit 51 and thence to the cutters 68. Coolant support bracket 51a forms an adjustable tie for the flexible conduit 51 to the overarms 65. The coolant is returned by collecting same in the T-slots and pockets 14g and 14h of table 14, the coolant flowing out through opening 14i in the table and being directed into 13k by the plates shown. The coolant is then returned to pan 11b by a tube 13x.

The hand and power controls for the table

The hand and power transmissions and controls for table 14 in the longitudinal, lateral and vertical directions are shown in Figs. 1, 7 and 8. The table 14 rests on saddle 13 and is held in place by dove-tail slide 14a, and a dove-tail slide formed by gib 13g which gib is shaped as shown in Fig. 1, and therefore cannot rise because it is formed to positively prevent same being lifted by the table 14 due to the shoulder 13h. Take up on gib 13g is accomplished by a series of screws 13m throughout its length (not shown) holding the gib 13g against the table.

Table 14 is driven longitudinally of the machine by screw 14b (Fig. 7) and nut 13b since table brackets 14c and 14d (Fig. 7) are securely bolted to the end of the table and hold the bearings that mount the table screw 14b. Saddle 13 is supported in knee 12 by a gib slide, and is driven towards the front or rear of the machine by screw 90c (Fig. 7) by engaging nut 13c. Knee 12 in turn is supported by gib slide 12a and is raised or lowered by screw 13d engaging nut 10d (Fig. 1) on column 10.

A particular advantage of my table drive is the fact that same is so designed that the drive to the longitudinal table screw 14b is divided so that the normal structure of the saddle 13 is such that the table 14 is held at a minimum distance from the knee 12, and the saddle 13, the length of which

must support the table 14 by the gib slides 14a and 13g, is utilized to form the housing for the longitudinal table drive transmission. The knee 12 supports the saddle 13 at about the middle of its length, and the saddle is formed to create two pockets 13e (Fig. 1) at each side of the knee 12 to house the necessary gearing. Therefore, the saddle 13 in my milling machine has a length which gives sufficient dovetail support for the table 14. This saddle has a width sufficient to form the proper support by the knee 12. Since these practical requirements for a well-designed saddle preclude the use of approximately these dimensions as to length and width of the saddle, I have made a definite practical gain in making use of these necessary dimensions and have added only sufficient depth to the saddle on each side of the knee to form the pockets 13e which house the longitudinal table drive gears. The table longitudinal gear transmission definitely reflects the expedient of dividing said transmission and putting a smaller portion to the right (Fig. 7) so that this smaller portion plus the electric motor which drives the table transmission closely approximates in weight the larger portion of the gear drive placed to the left (Fig. 7). Thus the weight and size at the right half of the saddle approximately equals the weight and size at the left half of the saddle. The result is a definite mechanical and structural advantage, as well as a very pleasing balanced appearance, as viewed from the front of the machine.

The longitudinal drive for the table 14 (Fig. 7) is powered by electric motor 70a through pinion 70b keyed on the motor shaft 70 and meshing with gear 71b integral with gear 71a which is keyed to countershaft 71 journaled in bearings at each end in saddle housing 13 (Figs. 1 and 7). Gear 71a meshes with gear 72a carrying a plate 72b riveted to it. In plate 72b are housed balls 72c that are spring loaded as shown in Fig. 14. These balls engage notches 72k in clutch sleeve 72d and when the torque is not sufficient to force balls 72c out of the way against their springs the driven plate 72b will rotate clutch sleeve 72d. Clutch sleeve 72d freely rotates on bushing 72e which together with sleeve 72f position it along sleeve 72 but permit its free rotation. When clutch sleeve 72g is pushed to the right by yoke 72h on shaft 72i, it engages the clutch teeth of sleeve 72d and rotates or drives the table screw 14b since clutch sleeve 72g is splined to sleeve 72 which in turn is splined to table screw 14b. Thus motor 70a drives table screw 14b through the nut 13b which is fixed to the underside of saddle 13, when the clutch teeth on sleeve 72g are engaged with clutch teeth on sleeve 72d, at a constant rate of speed which is the rapid traverse rate for table 14.

The selective feed rate drive for table screw 14b from motor 70a is as follows: Shaft 71 drives the keyed but slidable cluster gear 71c, 71e, which is brought into engagement with selective gear 73e, 73c, keyed to drive shaft 73 shown as broken in Fig. 7 but indicated in section in Fig. 1. Shaft 73 extends through saddle 13 and across the knee to drive pinion 73a (Fig. 7) which meshes with gear 74a keyed upon countershaft 74. A three-gear cluster 74b on shaft 74 meshes with gear 81a, 81b or 81c which together with gear 81d are keyed on sleeve 81e which is free to rotate on shaft 81 mounted in appropriate bushings in the saddle 13. The drive then continues to the three-gear cluster 82b which is slidably keyed to shaft 82. Pinion 82a is keyed on said shaft 82 and drives gear 83a

which is riveted to plate 83b which drives clutch sleeve 83d by means of spring loaded balls similar to those shown at 72c, in Fig. 14, the balls normally fitting into notches in clutch sleeve 83d in the manner shown in Fig. 14, whereby unless the torque for which the springs are set is exceeded, plate 83b will drive clutch sleeve 83d. A bushing 83e together with sleeve 83f holds clutch sleeve 83d endwise but allows free rotation thereof. When clutch sleeve 83g is moved to the left (Fig. 7) by yoke 83h on shaft 72i its clutch teeth mesh with clutch teeth on sleeve 83d and thus drives table screw 14b because of the fact that clutch sleeve 83g is splined on sleeve 83 which in turn is splined on shaft 14b.

The power drive from motor 10a continues from gear 83a to shaft 81 since gear 81f is in mesh with gear 83a and is keyed to said shaft 81 which drives through bevel gears 81g and 81h (Fig. 7) sleeve 81j to which gear 81h is keyed. Shaft 95 is slidably keyed to sleeve 81j and carries clutch 96f which is keyed thereon. When the trip rod lever 91a is in position shown (Fig. 7) trip rod 91 has moved yoke 91b against the action of spring 91c. A safety clutch assembly consisting of gear 91e, which has been drilled to receive spring loaded balls at each end of each hole, is held between the clutch teeth flange of sleeve 91d and collar 91f by nut 91g, and since 91d and 91f are slightly notched to receive the balls gear 91e will drive sleeve 91d unless the torque, to which the spring pressures to the balls are set, is exceeded. Gear 91e is shown in the drawings positioned so that the clutch teeth of 91d have been withdrawn from the clutch 96f and thus the power would not continue beyond clutch 96f. To effect a power drive from clutch 96f to clutch teeth 91d it is merely necessary to turn trip rod lever 91a to the opposite position from that shown in Fig. 7 so that spring 91c would move yoke 91d whereby gear 91e (and clutch sleeve 91d) would be moved into mesh with clutch 96f.

To effect power drive to the elevating screw 13d (Fig. 1) it is necessary to move trip rod handle 92a (Fig. 7) on trip rod 92 so that a flat 92x on trip rod 92 would allow gear 93a and its clutch teeth to come into mesh with clutch teeth 93f under the urge of spring 92c, whereby the drive would continue from gear 91e to gear 93a and hence to clutch teeth 93f on shaft 93 (Fig. 7) to which it is keyed; and hence from shaft 93 (Fig. 1) through the keyed bevel gears 93x, 93y to elevating screw 13d.

To effect a power drive to cross feed screw 90c of saddle 13 it is necessary to move trip rod handle 92a so that the flat on trip rod 92 at 92b would permit gear 90e to mesh with clutch teeth 90f on screw shaft 90c under the urge of spring 90d. Thus the drive from clutch 96f would continue from gear 91e to 93a and thence to 90e, and then to clutch teeth 90f. Nut 13c which engages shaft 90c is bolted to saddle 13. Gear 93a is mounted on a sleeve 93g which is flanged and held with screws in housing 94. Such construction eliminates the possibility of shaft 93 being rotated when clutch sleeve 93a and the clutch teeth 93f are disengaged and the drive is from clutch 96f and through the clutches to clutch teeth 90f and screw 90c. Trip rod 92 has the release flats on opposite sides so that it permits only one clutch pair to be meshed at a time. Thus it has been shown how the power drive can continue from clutch teeth on 93a to 93f to shaft 93, or can continue from 90e through 93a to

clutch 90f to screw 90c by the operation of hand lever 92a.

The hand operation of shaft 93 for operating the knee elevating screw 13d and the cross feed screw 90c of the saddle 13 is partly shown in Fig. 1. The hand wheel 95a is keyed to shaft 95 and pinion 95b. If it is desired to have this hand wheel turn during the power drive it is allowed to stay in mesh with gear 93a, otherwise a compression spring against pinion 95b is supplied to urge pinion 95b and shaft 95 and hand wheel 95a to one side to slide pinion 95b out of mesh with gear 93a, whereby the hand wheel 95a will not turn during the power drive. When hand drive is desired however, hand wheel 95a is pushed in bringing pinion 95b into mesh with gear 93a; and thus the hand wheel will turn all three gears 91d, 93a and 90e. The hand wheel drive can then be brought to shaft 93 or screw 90c by the action of hand lever 92a, for hand operation, in the same identical manner as when used for power operation. Dials 93h and 90h (Fig. 7) are graduated dials rotatably locked by thumb screws to elevating drive shaft 93 and the saddle cross feed screw 90c, respectively. A similar dial 14h is mounted on table screw 14b. Bearing 90g is mounted to take the thrust of cross feed screw 90c in both directions.

The three safety clutches or torque release mechanisms in my drive are uniquely placed, and serve a most important role of limiting the torques transmitted at their points of application in order to prevent breakage and to serve the further purpose of supplying that limit of torque which the gears must be designed to supply. The rapid traverse safety clutch built into plate 72b has slightly spring loaded balls 72c in shallow notches in clutch sleeve 72d because this safety clutch need only be set for light torque to deliver full motor horsepower because the speed of shaft 14b is high. A further advantage of this clutch is that, due to its light torque setting, the balls can ride back and forth in their shallow notches thus releasing the blow when subject to shock due to clutch engagements actuated by rod 72i or from quick motor reversal loads, thus the impact of engagement of the clutch teeth on sleeve 72d and 72g is greatly lessened. The feed safety clutch of plate 83b, which is generally similar to that of the plate 72b of Fig. 14, has heavily spring-loaded balls however, and sharp angled deep notches in the sleeve 83d, because this clutch must transmit very high torque which is supplied by motor 10a due to the fact that the speed has been greatly reduced through the gear feed transmission. This feed safety clutch together with the safety clutch built into gear 91e determines the torque limit to which the gears in most of the transmissions must be designed to meet. The safety clutch built into gear 91e is unique in that this safety clutch is in the power drive to the knee elevating screw 13d (shaft 93) and cross feed screw 90c of the saddle 13, but is not in the hand wheel drive, thus in the event the torque of this clutch is exceeded during power drive the safety clutch will release while in the case of the hand wheel drive the operator is not limited to the setting of the safety clutch.

The safety interlock

A safety interlock has been arranged at 75a (Figs. 7, 8 and 15) on shaft 75 so that the projected lug 75b when swung in place by hand knob 75c will prevent sleeve 75d from moving to the right (Fig. 7) against the internally mounted

compression spring 75x (which spring may be omitted) and which further prevents square pin 75e from moving to the right; and thus the clutch teeth on hand crank 75f cannot engage the clutch teeth on collar 75g which is pinned to the table screw 14b. Thus the hand operation by the hand crank 75f of the table screw is in this way prevented. When hand lever 75c is rotated to bring 75b out of the path of 75d, the hand crank 75f can be moved to the right (Fig. 7) until its clutch teeth mesh with clutch teeth 75g since pin 75e can then move 75d to the right under spring compression (when the spring is used); and therefore hand crank 75f will engage and drive the table screw 14b. Shaft 75 is keyed to pinion 75h (Figs. 8 and 15) which engages rack teeth 76x in the shaft 76 which may be pulled in or out by hand knob 76a to effect engagement and disengagement of projection 75b on 75a.

The mechanical trip from feed to rapid traverse of the table is accomplished by table trip dogs 14y (Fig. 15) bolted in the T-slot 14x (Figs. 1 and 15) which depress either plunger 13a or 13b (Figs. 8 and 15) and thus cause pinion 77a together with the shaft 77, to which it is keyed, to rotate. The trip dog that depresses plunger 13a is made so that it will depress same when moving in the chosen feed direction, but it will swing up and not depress this plunger when it goes over the plunger in the return direction. Shaft 77 (Figs. 1, 7 and 15) rotates pointed link 77b to the left or right, and since the circular lug on 77b engages a slot in trip rod 72i either clutch set 83d and 83g or 72g and 72d are caused to mesh. When pointed link 77b is being rotated it first travels through the idle space in the slot in rod 72i and proceeds under the point 78a in link 78 before it disengages a set of clutches. The link 78 under the urge of the tension in spring 78c begins to throw the pointed link towards the opposite clutch set before the first clutch set is disengaged, and therefore when the movement of the table has disengaged a set of clutches, pointed link 78a is in a position to force trip rod 72i to bring the other set of clutches into mesh, thus preventing the mechanism from coming to a dead stop.

In Figs. 8 and 15 cam plate 76b has the cam race 76c cut into it so that this cam race is engaged by pin 72k in shifter rod 72i, and when rod 76 is in the position shown in Fig. 8, shifter rod 72i is forced to neutral so that neither clutch is engaged. It is this position of rods 76 and 75 in which lug 75b is out of the way of 75d so that hand crank 75f can be engaged by hand as shown in Fig. 17. When hand knob 76a is pulled to the right in Fig. 15, pin 72k is freed so that shifter rod 72i can engage either set of clutches. 77d (also Fig. 1) is the hand lever for use in hand operating shaft 77 to select either feed or rapid traverse by the same means used in the power drive.

The vertical milling head

Figs. 2 and 3 illustrate the structural features of the vertical milling head 111, 112, which is fastened to column 10 by means of a hinge 110 bolted to the side of column 10. The hinge pin 110a is securely positioned in hinge 110, so that when it is desired to move the vertical head 111, 112, into and out of position it is only necessary to swing it about pin 110a. The drive for spindle 125 is taken from horizontal spindle 25 through V-pulley 105 and from thence by V-belts to V-pulley 106, through shaft 107, and through bevel

gears 108 and 109 to sleeve 108a journaled in casting 112a and supported by the vertical housing 112. Spindle 125 is slidably keyed in sleeve 108a and is journaled in sleeve 126 which in turn slides in vertical housing 112 under the urge of hand wheel 126a operating screw 126b which engages nut 126c bolted to sleeve 126. Great rigidity for sleeve 126 is obtained by making same relatively large and long and providing a drive on the inside of it supported as shown with the slot 126d arranged to clear bevel pinion 108. Vertical housing 112 is supported both at 112a and 112b and is supported so that it can rotate in housing 111. Housing 112 is split for a distance up from its bottom so that screw 112c can be used for take up for wear, and clamp and screw 112d can be used to clamp sleeve 126 in housing 112. Screws 112e are used to clamp plates 112f against the groove 112g to effect clamping between housings 111 and 112. Nut 110b is rotatable on the threaded lower end of hinge pin 110a, which pin in turn is secured in hinge 110 by the screws 111a, and this nut 110b is used to raise and lower housing 112 by contact against lug 112b to tighten or loosen the V-belts between V-pulleys 105 and 106. Four clamping screws 111a are shown used to bolt housing 111 securely against column 10 in addition to hinge 110. Screw and nut 126e are used to form an adjustable stop against which nut 126c engages when a limit stop for the downward travel of sleeve 126 is desired.

The hand shifting of the table feed change gears

The hand direct shifting of the table feed change gears is shown in Fig. 7. Yoke 87a is shown extended to position cluster gear 74b by a yoke disposed between two gears thereof but allowing their free rotation. Similar yokes (not shown) position cluster gear 82b and cluster gear 71c, 71e. Yoke 87a is pinned to shaft 87 and is shifted by means of hand lever 87g. In the event that the gear teeth of the gear being shifted should hit the face of its mating gear, handle 87g which is pinned to housing 87b can be moved on into the correct position and be locked by means of pin 87i in cam slots in 87b. Thus when moving handle 87g into desired position the spring 87h in housing 87b is compressed and urges collar 87c against the shoulder on shaft 87, and thus continues to urge yoke 87a toward the desired position. As soon as motor 10a is started, shaft 14 will turn cluster gear 74b into the correct position for meshing. If hand lever 87g is moved to the left and locked into position by pin 87i and cluster gear 74b is being moved to the left but cannot reach its correct position due to striking mating tooth faces, the shaft 87 will force collar 87d which is pinned to the shaft 87 through collar 87e, which is pinned to 87g, and force collar 87f to the right, compressing spring 87h against collar 87c which is stopped at the end of the counterbore in which it rides in 87b. Thus the position of cluster gear 74b can be preselected by hand lever 87g, and if cluster gear 74b cannot move it will be urged to do so by spring 87h until the gears are so revolved that they can mesh properly.

The dial selector

The hand shifting may be accomplished by the dial selector shown in Figs. 10 and 11 which is done by shifting sleeves 87b1, 87b2 or 87b3 by mechanical means rather than individually by hand; but the fundamental mounting of springs similar in operation to 87h are used, so that the shifting movement may be accomplished even

though cluster gears, similar to 74b, cannot immediately be moved to their correct positions. The mechanical gear shifting device is operated by hand crank 88a (Fig. 10) which is pinned to shaft 88 which in turn carries gear 88b and a link 88c which carries shifting pin 88d, so that when crank 88a is pushed in against spring 88e to release pin 88d from housing 13, it can be rotated from positions 1, 2 and 3, shown in Fig. 11. Sleeve assembly 87b3 carries a yoke similar to 87a that links into 82b to mesh 82b with 81d for position 1, with 81b for position 2 and with 81a for position 3. Gear 88b drives gear 89b so that three turns of handle 88a are required to make one rotation of cam 89c on shaft 89. Cam track 89d is so formed that when handle 88a is rotated to the left (Fig. 11) to assume position 1, 2 and 3 follower pin 89e remains stationary, but when rotated from position 3 to 1 follower pin 89e moves link 89f from its present position and carries 87b2 to the left. When hand crank 88a is rotated again from positions 1, 2 and 3 follower pin 89e does not move, but when moved from position 3 to 1 link 89f carries 87b2 to its left position. As link 87b2 slides 74b with yoke 87a it successively meshes 74b with 81a, 81b and 81c. When crank 88a is rotated to position pin 88d successively from 1 to 3 again 89e does not move. When 88d is now moved from 3 to 1 cam track 89d carries roller 89e back to the position shown and notch 89g allows the tension of accumulated over travel of 87b1 to pivot link 89h into intimate engagement with 89g and thus link 89h is forced to pivot with 89m to move 87b1 to the left. 87b1, through a resilient connection, is yoked to cluster gear 71c, 71e and thus pulls 71e from mesh with 73e and meshes 71c with 73c. When 88 is again rotated this entire shifting of links 87b3 and 87b2 are repeated to complete all gear selections. Thus I have shown how the turning of a hand crank 88a will shift the feed drive gear to positions giving the minimum speed to the positions giving maximum speed. If the hand crank 88a is turned in the opposite direction the entire operation of the mechanism will be repeated in the reverse order. A dial containing two rows of figures is carried at 89j on dial hub 89k which is keyed to shaft 89 and indicates both the low nine and high nine feeds. Dial 89l or any convenient means that indicates the position of 89h is keyed to pivot pin 89m which is keyed to link 89h so that when link 89h is shifted by the selector dial, 89l indicates whether the low or high series of feeds are in use. The great convenience of this dial selector makes it attractive over the direct hand shifting means in that it is only necessary to turn crank 88a repeatedly to obtain feed desired as indicated by dial 89l or any similar means and dial 89j.

The electric circuit

The electrical diagram as shown in Fig. 9 depicts many usual constructions commonly used in the pilot control for the operation of electrical motors. The portion of the diagram labeled table reversing controller shows a reversing controller fed from the power lines L1, L2 and L3. These three lines are regular incoming power lines. The hold-in coil for engaging the contacts to operate the motor to propel the table to the right is shown at R. R1 gives the position that this hold-in coil would assume in the control of the table motor. Likewise LT1 shows the position that the hold-in coil LT would assume to operate the motor in the other direction.

Thus when coil R is energized the table will be driven to the right by the table motor. Also when coil LT is energized the table will be driven to the left. Spindle motor is operated through the three line contacts labeled on spindle controller as S1, which contacts are closed by solenoid coil S when it is energized because this coil is actually in position at S1 to properly perform this function. Connections are made so that the coolant motor will run when coil S is energized providing switches C1, C2 and C3 are connected as shown to the upper set of contacts. If switches C1, C2 and C3 are connected to the lower set of contacts the coolant motor will be connected directly to the line and thus receive the necessary incoming power to run. The spindle direction switch is a manually operated direction switch. When all switch links like D3 are positioned by a single manual lever (not shown) and swung to the left the spindle motor will run in one direction when the switch links are swung to the right the spindle motor will run in the opposite direction. When the switch links are positioned vertically as shown, the spindle motor is cut off from power and therefore will not run. The notation OL labels a safety release placed to protect the motors against overload. There are two sets of push buttons used on the milling machine—one at front marked in the diagram Front and the other set marked Rear on diagram. Each has three push buttons Right, Stop, Left, respectively for both sets of push buttons. The double brake contacts marked "knee" and "saddle," are placed in series with the two stop push buttons. The double brake contact marked "knee" is depressed by mechanical trips on the knee and therefore stop the knee at a predetermined place or at the limit of its travel. The contact marked "saddle" functions in a like manner for the saddle. The contact labeled "LT hold-in" is the standard hold-in contact that is regularly closed when solenoid coil LT is energized and moves bar LT1 to close the three contacts for this portion of the table reversing controller. The contact labeled "R hold-in" is the standard hold-in contact that is regularly closed when solenoid coil R is energized and moves bar R1 to close the three contacts for this portion of the table reversing controller. The limit switch marked RLS has a double set of contacts one of which is normally open and one is normally closed. This limit switch is located at the right end of the saddle and is tripped by table dogs (not shown) in T slot 14b in table 14, when the table is travelling towards the left. The limit switch has a snap action and is loaded by the action of the table dog and trips instantly all the way from the normally closed position to close the contacts that are normally open and opens the contacts that are normally closed. Limit switch marked LLS is identical in construction and operation except that it is located at the left end of saddle and is tripped by table dogs when the table is moving to the right. That portion of the diagram enclosed by the dotted rectangle and labeled "Automatic control switch" is operated by a single manual handle (not shown) which moves all switch links like E3 to the left when turned towards RL and brought to a vertical position shown when single manual handle is brought to neutral and pointing to H, and swings all switch links like E3 to the right when single manual handle is turned toward the right and brought to RR.

I have specified and explained all portions of the detailed elements of this wiring diagram and have positioned these elements in the diagram so that I can now explain its operation which has been completely proven and demonstrated by actual tests on an existing milling machine. It is apparent that the incoming power lines L1, L2 and L3 is made available to all motors in the bottom half of the diagram. The top half of the diagram embodies the control circuit. It will be noted that one side of each coil R, S and LT is connected to L3, it will be further noted that L2 is carried to the extreme right of the diagram and completes several connections. T2 is brought from the table motor up to a contact on the control switch.

When single manual handle is positioned at H, as explained above, pressing right push button on either front or rear push button station will energize coil R as L2 can easily be traced to show that coil R is energized because this coil receives power from both L3 and L2. Energizing coil R closes controller R' and starts table motor to drive table to the right.

Table motor will continue to run because R hold-in will be closed and L2 can be easily traced to R through R hold-in. When table motor is started, power from T2 can be traced to coil S and energizes it so that spindle motor will start if spindle direction switch has been manually set for either direction of rotation. Coolant motor will run if switches C1, C2 and C3 are positioned as shown. When the table has continued in its travel until the dog on the left end of the table hits limit switch LLS the energizing circuit to R will stop and thus table motor will stop causing S to be deenergized and therefore the spindle motor and coolant motors will stop. When left push button is pressed coil LT is energized as can be seen by tracing L2 to coil LT when table motor will drive table to the left, spindle motors and coolant motors will operate. Table motor will continue to run because LT hold-in will close. When the table dog on right end of table trips RLS the table motor will stop and thus cause spindle motor and coolant motor to stop. It is thus seen that when single manual handle on automatic control switch is positioned at H (meaning hand) the milling machine table 14 will be driven to the right when "right" push button is pressed, will go to the left when left push button is pressed and will stop when either left or right limit switch is tripped, or the table can be stopped by pushing stop button in either front or rear push button station and it was shown that whenever the table motor runs the spindle will run and the coolant will flow.

When single manual handle is turned to the left toward RL the machine will operate as above when the right push button is pushed. But when table has proceeded to the point where the table dogs trips LLS the spindle motor will be reversed because R is deenergized and LT is energized but in this case the spindle motor is stopped because it was being energized along line F3 which is broken by LLS. Thus, the table will return to the left but spindle and the coolant will stop during this return travel of the table.

When single manual handle is turned toward RR and left push button is pressed in a similar manner as explained above, table will be driven to the left and spindle and coolant will start and when a table dog trips RLS, R will be energized and table will return to the right but spindle and

coolant is stopped because coil S is no longer energized through G3.

When the milling machine is operated as explained above through its automatic cycle the electric controls determine its direction of travel and the synchronizing of the spindle and coolant operation. The feed or rapid traverse rates are determined mechanically by the direction that shifting rod 72 is shifted (see Figs. 7 and 8). 10 When the machine is run either by hand control of each table movement or by automatic control of a complete table cycle the front push button station 94a in Fig. 1 or the rear push button station, both of which are shown in Fig. 9, 15 remains in control so that the milling machine can always be started, reversed or stopped no matter where the table is positioned.

Alternate horizontal spindle drive

20 The drive to the horizontal spindle 25 on column 10 as shown in Fig. 1 is advantageously simple in operation because the movement of one cluster gear 25b and 25c complete the mesh with their mating gear as well as completing the engagement of the direct drive between the internal clutches in 25b (not shown) and the clutch teeth 36x on the end of sleeve 36. The alternate drive to the horizontal spindle as shown in Figs. 13 and 12 is included because gears 225a and 225b can be affixed rigidly to the spindle. This alternate drive to the horizontal spindle would be used on the milling machine when manufactured for specially heavy work to gain the advantage of rigidly affixing 225a and 225b to the spindle 225 and avoiding the looseness between the gears and the spindle that would otherwise be unavoidable when these gears must be slid along the spindle to complete the proper intermesh of the gears and clutches. A further gain obtained 25 from the alternate drive is that the fly wheel effect of gears 225a and 225b in assisting the cutting teeth in cutter 68 penetrate the surface to be cut and smoothly progressing through the cut to give quality finish, is more pronounced when the gears 225a and 225b are definitely affixed to spindle 225 and not slidably mounted thereon.

30 The alternate drive to horizontal spindle involves a different shifting means because of the fact that both gears 139b and 139c are moved as well as the second part consisting of a clutch sleeve 225d must be moved.

35 The alternate drive to horizontal spindle as shown in Fig. 13 is powered by belt 34. Belt 34 continues from the V-pulleys 31a and 31b exactly identical to the method previously described and shown in Fig. 1. Pulley 35 again drives sleeve 36 which has pinion 36a cut integral with it. Pinion 36a is in constant mesh with gear 139a which is keyed to shaft 139. Gears 139b and 139c are 40 keyed and slidably mounted on shaft 139 and can be moved into mesh with gear 225b or 225c or can be moved out of mesh as shown in Fig. 13. Clutch sleeve 225d is slidably keyed to spindle 225. Thus spindle 225 can be rotated in slow speed by meshing 225c and 139c; in middle speed by meshing 225b and 139b; and in high speed by meshing 225d with the clutch teeth on 36a.

45 Cluster gears 139b and 139c are moved by the extended yoke partially shown at 150 in Fig. 12. Yoke 150 is resiliently mounted on shifter shaft 151 by two U-shaped sliding collars 150x mounted on the reduced portion of shaft 151 and abutting against a compression spring 150a. Collars 150x also abut against the counterbore in yoke 150 on one side and against a similar type shoul-

der produced in any convenient way as shown. Thus when hand lever 152b rotates rod 152 to which it is pinned, gear 152a is rotated because it is keyed to 152 and thus rod 151 is moved laterally as gear 152a meshes rack teeth in 151. If yoke 150 cannot complete the mesh of the gears spring 150a is compressed until the teeth are rotated into mesh. When hand lever 152b is moved to position yoke 150 so that gears 139b and 139c are in neutral position as shown in Fig. 13 a deep hole is arranged so that pin 152c can penetrate it and allow shaft 152 to move gear 152a and allow bell crank to move about its pivot to permit spring 153a to force shaft 153 to the left and thus carry yoke 153c to the left and thus carry clutch sleeve 225d, which is engaged by yoke 153c, to the left to mesh clutch 225d with clutch teeth of pinion 36a. It is therefore shown how hand lever 152b will mesh clutch sleeve 225d with clutch teeth of 36a and also mesh gear 139b to gear 225b and gear 139c with gear 225c to complete the drive from pulley 35 to spindle 225 giving the three speeds. A deep hole as explained above is available to insert pin 152c into it to allow bell crank 153b to complete the mesh of clutch teeth on clutch sleeve 225d. Two shallow holes are used (not shown) to allow pin 152c to enter a short distance to lock hand lever 152b into each of the two positions of this hand lever that mesh 139b and 225b or 139c and 225c. When pin 152c enters these two shallow holes gear 152a moves only slightly under the urge of spring 153a and bell crank 153b but the slight amount of movement of shaft 153 is not enough to mesh the clutch teeth on clutch sleeve 225d by action of the yoke 153c which is keyed to shaft 153. Thus spring 153a acts to force both the meshing of the clutch teeth on clutch sleeve 225d and also acts to force pin 152c into its locked positions through the action of the bell crank 153b.

I claim:

1. In a milling machine, a base, a column having a spindle; a vertically movable knee mounted on said column; a transversely movable saddle mounted on said knee and carrying a fixed nut; a longitudinally movable table mounted on said saddle; a feed screw shaft journaled in said table and engaging the nut; a motor mounted in one end of the saddle; a clutch member floating on the adjacent end of the shaft and constantly driven by said motor for rapid traverse movement of the table; a second clutch member floating on the opposite end of the screw shaft; change speed gearing mounted in the opposite end of the saddle and adapted to constantly rotate the second clutch member for selective feeds of the table; means for driving the change speed gearing from the motor; movable clutch elements splined on the shaft adjacent their respective floating clutch elements, and a common actuating member for alternately shifting the movable clutch elements into engagement with their related floating clutch elements.

2. In a machine as set forth in claim 1, said motor and drive for the first floating clutch member being disposed in a depressed pocket of the saddle below the table at one side of the saddle; and the change speed gearing for the second floating clutch member being disposed in a second depressed pocket of the saddle below the table at the opposite side of the saddle, whereby the weights of the divided table drive will be approximately balanced at each side of the saddle.

3. In a machine as set forth in claim 1, each floating clutch element including a clutch sleeve

on the shaft; a plate rotated by the motor; spring pressed balls housed in radial recesses in the plate and engaging notches in the clutch sleeve, thereby providing a safety clutch whereby the sleeve will be rotated by the balls only until the torque for which their springs are set is exceeded.

4. In a machine as set forth in claim 1, each floating clutch element including a clutch sleeve on the shaft; a plate rotated by the motor; spring pressed balls housed in radial recesses in the plate and engaging notches in the clutch sleeve, thereby providing a safety clutch whereby the sleeve will be rotated by the balls only until the torque for which their springs are set is exceeded, the springs for the balls of the first floating clutch member being light and the notches in the sleeve shallow for delivering full motor horsepower at light torque at high speed of the feed screw shaft, while the springs for the balls of the second floating clutch member being heavy and the notches sharp angled for delivering high torque at reduced speeds of the feed screw shaft.

5. In combination, a machine as set forth in claim 1, a hand crank journaled adjacent the feed screw shaft; a normally disengaged clutch between the crank and shaft; a manually rotatable shaft beside the screw shaft; and a lug on said manually rotatable shaft adapted in one position to engage the said clutch.

6. In combination, a machine as set forth in claim 1, a hand crank journaled adjacent the feed screw shaft; a normally disengaged clutch between the crank and shaft; a manually rotatable shaft beside the screw shaft; and a lug on said manually rotatable shaft adapted in one position to engage the said clutch; said manually rotatable shaft carrying a pinion; and a manually operable pull rod having rack teeth meshing with said pinion.

7. In a machine as set forth in claim 1, a pair of spaced plungers mounted in the saddle adjacent one edge of the table; shiftable trip dogs on the table adapted to actuate the plungers; and a manually rotatable crank shaft underlying the common actuating member and having a member engaging a cam slot in the common actuating member whereby as the crank shaft is rotated in either direction the actuating member will be shifted accordingly to engage either the feed or rapid traverse clutches selectively.

8. In a machine as set forth in claim 1, a pair of spaced plungers mounted in the saddle adjacent one edge of the table; shiftable trip dogs on the table adapted to actuate the plungers; and a manually rotatable crank shaft underlying the common actuating member and having a member engaging a cam slot in the common actuating member whereby as the crank shaft is rotated in either direction the actuating member will be shifted accordingly to engage either the feed or rapid traverse clutches selectively; said cam slot having an idle space; a spring-pressed link having a pointed projection under which the crank passes before shifting the common actuating member to disengage a clutch set, said pointed projection throwing the crank towards the opposite clutch set before the first set is disengaged, whereby when the movement of the table has disengaged a set of clutches the spring-pressed link will be in a position to force the common actuating member to engage the other set of clutches while preventing the mechanism from coming to a dead stop.

9. In combination, a machine as set forth in claim 1, a hand crank journaled adjacent the feed screw shaft; a normally disengaged clutch between the crank and shaft; a manually rotatable shaft beside the screw shaft; and a lug on said manually rotatable shaft adapted in one position to engage the said clutch; said manually rotatable shaft carrying a pinion; a manually operable pull rod having rack teeth meshing with said pinion; a cam plate carried by the pull rod and having a cam race; and a pin on the common actuating member, whereby when the pull rod is in position to release the lug and engage the hand crank with the feed screw shaft, both sets of clutch elements will be disengaged from the power feed, and whereby when the pull rod is in position to disengage hand crank, the cam race will free the pin so that the common actuating member can engage either set of clutch elements.

10. In a milling machine, a base, a column having a spindle; a vertically movable knee mounted on said column; a transversely movable saddle mounted on said knee and carrying a fixed unit; a longitudinally movable table mounted on said saddle; a feed screw shaft journaled in said table and engaging the nut; a motor mounted in one end of the saddle; a clutch member floating on the adjacent end of the shaft and constantly driven by said motor for rapid traverse movement of the table; a second clutch member floating on the opposite end of the screw shaft; change speed gearing mounted in the opposite end of the saddle and adapted to constantly rotate the second clutch member for selective feeds of the table; means for driving the change speed gearing from the motor; movable clutch elements splined on the shaft adjacent their respective floating clutch elements, and a common actuating member for alternately shifting the movable clutch elements into engagement with their related floating clutch elements; change speed gearing in the spindle drive; manual control means for shifting the change speed gearing of the spindle drive; separate manual control means for shifting the change speed gearing of the feed shaft drive; and a dial selector for setting the change speed gearing of the feed shaft drive.

11. In a machine as set forth in claim 10, said change speed gearing for the spindle drive and feed shaft drive including intermeshing cluster gears; yokes engaging the respective cluster gears; manually rotatable shafts for operating said yokes; hand knobs on said shafts having pins adapted to engage slots in their supporting elements; and yieldable connections between the hand cranks and shafts for urging the yokes into the preselected positions to which the hand cranks are set, whereby in event the teeth of the cluster gears should initially strike when shifted, the yokes will move said gears into meshing relation whereby the gears will mesh when same have been rotated relatively into meshing positions.

12. In a machine as set forth in claim 10, said change speed gearing for the feed shaft including intermeshing cluster gears; yokes for operating the respective cluster gears; sliding sleeves operated by the dial selector and carrying said yokes; yieldable connections between the sleeves and yokes for urging the yokes into preselected positions to which the sleeves are set, whereby in event the teeth of the cluster gears should initially strike, the yokes will move said gears into meshing positions whereby the gears will mesh when the gears have been rotated relatively into meshing positions.

13. In a machine as set forth in claim 10, said dial selector comprising three shifting rods operating the change speed gears; a normally locked slidable shaft having a hand crank and having an offset pin adapted to engage a slot in one rod when the shaft is shifted; a pinion on said shaft; a gear meshing with said pinion and making one-third of a revolution for each revolution of the pinion; a circular plate having a cam track carried by said gear; a link having a follower engaging said track and operating the second rod; a pivoted link having one end engaging the third rod and its other end overlying the periphery of the plate; said plate having a notch whereby during one arcuate movement of the plate the tension of the accumulated overtravel of the third rod will cause the link to pivot its other end into intimate engagement with the notch and shift the third rod; and said track being so shaped that turning the hand crank through successive rotations will progressively shift the feed shaft drive from minimum gear ratio to maximum with respect to the speed of the motor shaft.

14. In a milling machine, a base, a column having a spindle; a vertically movable knee mounted on said column; a transversely movable saddle mounted on said knee and carrying a fixed nut; a longitudinally movable table mounted on said saddle; a feed screw shaft journaled in said table and engaging the nut; a motor mounted in one end of the saddle; a clutch member floating on the adjacent end of the shaft and constantly driven by said motor for rapid traverse movement of the table; a second clutch member floating on the opposite end of the screw shaft; change speed gearing mounted in the opposite end of the saddle and adapted to constantly rotate the second clutch member for selective feeds of the table; means for driving the change speed gearing from the motor; movable clutch elements splined on the shaft adjacent their respective floating clutch elements, a common actuating member for alternately shifting the movable clutch elements into engagement with their related floating clutch elements; a slidable shaft journaled in the knee and extending to the front of the machine and driven by said change speed gearing and carrying a fixed clutch element; a sliding clutch element on said shaft carrying a gear; means for engaging and disengaging the slidable and fixed clutch element; a knee elevating shaft journaled in said knee; a saddle cross-feed screw shaft journaled in said knee; and means for selectively rotating the knee and saddle shafts from said gear.

15. In combination with a machine as set forth in claim 14, said sliding clutch element including a sleeve upon which the gear of the sliding clutch rotates; said sleeve having an enlargement beside the gear provided with notches in its adjacent face; said sliding clutch gear having bores registering with said notches; and opposed spring load balls in said bores, thereby providing a safety clutch whereby the gear will be rotated by the balls only until the torque for which the springs are set have been exceeded.

16. In a machine as set forth in claim 14, said selective rotating means comprising fixed clutch elements on the knee elevating shaft and saddle cross-feed shaft respectively; sliding clutch elements on said knee and saddle shafts; said sliding clutch elements having intermeshing gears one of which constantly meshes with the gear on the sliding clutch element of the sliding shaft;

and means for shifting the sliding clutch elements of the knee and saddle shafts into engagement with their related fixed clutch elements to drive the knee and saddle shafts from the sliding shaft.

17. In a machine as set forth in claim 14, said selective rotating means comprising fixed clutch elements on the knee elevating shaft and saddle cross-feed shaft respectively; sliding clutch elements on said knee and saddle shafts; said sliding clutch elements having intermeshing gears one of which constantly meshes with the gear on the sliding clutch element of the sliding shaft; and means for shifting the sliding clutch ele-

ments of the knee and saddle shafts into engagement with their related fixed clutch elements to drive the knee and saddle shafts from the sliding shaft; and a hand crank shaft movably mounted beside the knee elevating shaft and having a gear adapted to mesh with the gear on the sliding clutch element of the knee elevating shaft; and means for normally shifting the movable shaft to disengage said gears, whereby said knee elevating shaft and saddle cross-feed shafts may be manually rotated independently of the power feed.

ROBERT S. CONDON.
